UNITED STATES PATENT OFFICE

FRANK E. HORNBECK, OF FOREST CITY, PENNSYLVANIA

SIGN

Application filed January 7, 1930. Serial No. 419,116.

This invention relates to signs, and has particular reference to a mounting for outdoor signs which are subject to the action of the wind.

The invention broadly comprehends in a sign of the character set forth, means for mounting or supporting the sign board or panel to turn on a vertical axis in response to wind pressure whereby to relieve the mounting or support of stresses or strains which might otherwise tend to damage the sign or its mounting.

As a further object, the invention comprehends in a sign of the character specified, means constituting a part of the mounting which functions to gravitationally return the sign to a predetermined normal position after the wind dies down.

As a further feature, the invention aims to provide in a turnably mounted sign, an adjustable connection between the sign panel or board and its mounting for varying the preponderance of the area which is disposed on one side of the axis of the mounting to compensate for variation in the wind pressure due to the locality at which the sign is placed or the season of the year at which high winds occur.

Other objects of the invention reside in the particular construction of the mounting, with reference to the manner in which the elements of the mounting are guided in their relative movement and with reference to the manner in which the sign panel is removably carried to permit of its being lettered at a point remote from the installation of the sign.

Other objects reside in the simplicity of construction of the sign, the economy with which it may be produced and installed and the general efficiency derived therefrom.

With the above recited and other objects in view, reference is had to the following description and accompanying drawings, in which there is exhibited one example or embodiment of the invention, while the claims define the actual scope of the same.

In the drawings:

Figure 1 is a perspective view of a sign constructed and mounted in accordance with the invention.

Figure 2 is a vertical sectional view therethrough taken approximately on the line indicated at 2-2 in Figure 1.

Figure 3 is a fragmentary vertical sectional view illustrating the adjustable connection 55 between the sign and its mounting.

Figure 4 is a fragmentary sectional view illustrating the means for retaining the sign panel in its frame.

Figure 5 is an enlarged horizontal view 60 taken approximately on the line 5-5 of Figure 2.

Figure 6 is a fragmentary horizontal sectional view taken approximately on the line 6-6 of Figure 2.

Figure 7 is a plan view of the ball race.

Figure 8 is a detail perspective view of the retaining strip for holding the sign panel in the frame.

Referring to the drawings by characters of reference, 10 designates a sign panel or board which may be of any desired construction and which is preferably of flat rectangular configuration and removably carried by a frame 11 which is open at one end to permit of the 70 emplacement or removal of the sign therethrough, a retaining strip 12 being provided for closing the open end of the frame. In practice, the retaining strip 12 is preferably held in place by means of threaded studs 13 80 carried by the frame which engage through apertures 14 of the retaining strip, nuts 15 being applied to the threaded studs. The means for mounting the frame and panel for turning movement on a vertical axis consists 85 of a stationary pedestal 16, which is preferably of hollow tubular construction, suitably carried by a base 17 which may be embedded in the ground. The pedestal 16 rotatably supports a trunnion 18 which is also prefera- 90 bly of tubular construction and which telescopedly fits over the upper end of the pedestal 16 and which trunnion is provided with an inclined lower end 19 designed to rest on ball bearings 20 which are carried by a ball race 21 supported in an inclined position on the inclined upper end 22 of the stationary tubular outer shell 23 which surrounds the lower portion of the pedestal and 95 is held against rotation with respect to the 100

pedestal by means of set screws 24. The upper end of the trunnion 18 has telescopically fitted thereover a cap 25 which is formed with spaced parallel upstanding flanges 26 and 27 adapted to snugly receive the lower portion or rail of the frame 11. The flange 27 is provided with longitudinally extending slots 28 through which set screws 29 extend, the inner ends of the set screws being threadedly anchored in the lower portion or rail of the frame 11. The cap 25 is further provided with a boss 30 which is formed with a recess 31 receiving a threaded stem 32 which extends through a depending apertured lug 33 on the lower portion or rail of the frame 11. By loosening the set screws 29 and turning the threaded stem 32, it is apparent that the frame 11 and panel 10 are longitudinally adjustable with respect to the axis on which they turn, thereby varying proportionately the areas of the panel which are disposed on opposite sides of the axis. Binding nuts 34 and 35 are threaded on the stem 32 to engage with the opposite sides of the lug 33 to assist in retaining the panel and its frame in their adjusted relation. The cap 25 is secured to the trunnion 18 for turning movement therewith by means of set screws 36. It will also be observed that due to the inclined lower end 19 of the trunnion, that turning movement of the trunnion under the force of the wind pressure exerted on the panel will elevate the trunnion and panel to offer some resistance to the wind pressure and to cause the panel and trunnion to gravitationally return to a normal predetermined position. In order to guide the trunnion with respect to the pedestal 16, radially disposed screws 37 are threaded through the trunnion 18, and said screws have mounted in their inner ends anti-friction balls 38 which bear against the outer periphery of the upper end of the pedestal. The screws obviously are adjustable to compensate for wear and are retained in their adjusted position by binding nuts 39. The ball bearing screws 37 therefore serve to guide the trunnion with respect to the pedestal, both in a vertical and horizontal direction. In order to cover, protect and conceal the joint between the trunnion 18 and the shell 23, a sleeve 40 is provided which is telescopically arranged over the lower end of the trunnion and secured thereto by set screws 41. The lower end of the sleeve extends downwardly over the upper portion of the shell 23, as clearly shown in Figure 2 of the drawings. In order to retain a quantity of lubricant between the pedestal 16, the shell 23 and the lower portion of the trunnion, a retaining ring 42 is positioned between the shell 23 and the pedestal at a point slightly below the upper end of the shell.

From the foregoing, it will thus be seen that a sign has been devised which is mounted in such manner as to turn with the wind

by disposing a greater portion or preponderance of its area at one side of the vertical axis on which it is mounted, in order to relieve the sign and its mounting of undue strain from excessive wind pressure, which might otherwise tend to injure the same. It will be further observed that the mounting insures the normal positioning of the sign in a predetermined position when the wind dies down or lacks sufficient force to maintain the same in its turned elevated position.

What is claimed is:

1. In an outdoor sign, a sign panel disposed in a vertical plane, a vertical hollow cylindrical trunnion by the upper end of which the sign is carried, and means for supporting the trunnion for rotation on a vertical axis, including a vertical stationary cylindrical pedestal over which the hollow trunnion is arranged and circumferentially spaced elements extending radially through the trunnion and provided with anti-friction terminals bearing against the periphery of the pedestal.

2. In an outdoor sign, a sign panel disposed in a vertical plane, a vertical hollow cylindrical trunnion, by the upper end of which the sign panel is carried, and means for supporting the trunnion for rotation on a vertical axis including a vertical stationary cylindrical pedestal over which the hollow trunnion is arranged and circumferentially spaced elements extending radially and adjustably through the trunnion and provided with anti-friction elements bearing against the periphery of the pedestal for guiding the trunnion in its movements.

3. In a sign, a hollow cylindrical trunnion rotatable on a vertical axis, a sign panel adjustably mounted on the upper end of said trunnion for the purpose of presenting a greater area of the sign on one side of its axis than on the other, an upstanding cylindrical pedestal constituting a fixed support over which the trunnion is arranged and inter-engaging coacting means on the support and trunnion for causing the sign panel and trunnion to be elevated upon turning movement thereof and allowing said panel and trunnion to gravitationally return to a normal position in the absence of wind pressure, and means for guiding said trunnion in its axial and rotary movements, said means consisting of circumferentially and axially spaced elements extending radially through the trunnion and having antifriction terminals bearing against the periphery of the pedestal.

FRANK E. HORNBECK.
